UNITED STATES PATENT OFFICE.

LEWIS GIBBS, OF CANTON, OHIO.

DESIGN FOR A LAWN-RAKE.

SPECIFICATION forming part of Design No. 23,660, dated September 25, 1894.

Application filed July 30, 1894. Serial No. 519,035. Term of patent 14 years.

To all whom it may concern:

Be it known that I, LEWIS GIBBS, a citizen of the United States, and a resident of Canton, county of Stark, State of Ohio, have invented and produced a new Design for Lawn-Rakes, of which the following is a full, clear, and exact description, reference being had to the accompanying drawing, making part of this specification.

- My invention relates to a design for lawn rakes.

In the drawing, in which the rake is represented in perspective, A denotes the rake head circular in cross section; B, the handle socket tapering from one end to the other, and provided with laterally diverging arms, and B' the handle.

C denotes the teeth formed with parallel inclined inwardly projecting lower ends C⁴ terminating in hooks C' and the converging upper ends C³ united at their upper ends and inclined inward.

What I claim is—

The design for a lawn rake as shown and described.

In testimony whereof I have hereunto set my hand this 26th day of July, A. D. 1894.
